ABSTRACT

A conventional envelope signal forming circuit for producing percussive envelope signals in an electronic musical instrument is improved by the provision of a circuitry for setting a control voltage which is utilized to control a charge-discharge capacitor therein so as to reduce the overlapping of a plurality of envelope signals in one aspect of this invention and to allow the envelope signal to have a controllable sustained portion in another aspect thereof.

ENVELOPE SIGNAL FORMING CIRCUIT

BACKGROUND OF THE INVENTION

This invention relates generally to an envelope signal forming circuit in an electronic musical instrument and more particularly, it relates to the control of the waveform of the envelope signal produced from an envelope signal forming circuit to be supplied to a tone keyer circuit.

Heretofore, an envelope signal forming circuit as shown in, for instance, FIG. 1 has been employed in connection with the tone keyer of a musical instrument, in order to produce percussive tones having an abrupt build-up and a subsequent gradual decay.

In this circuit (FIG. 1), one terminal of a charge-discharge capacitor C_1 is connected through a reverse-current blocking element D_1 such as a diode to a first terminal of a charge-discharge capacitor C_2 , while the other terminal of the capacitor C_1 is connected to the positive terminal of the power source E through a charging resistor R_1 and a key switch K which is one of the keys in a keyboard.

Upon closure of the key switch K , charging the capacitors C_1 and C_2 is started through a circuit loop consisting of the power source E , the key switch K , the resistor R_1 , the capacitor C_1 , the diode D_1 , the capacitor C_2 , and the ground line. In this operation, a voltage developed at the output terminal T_1 connected to the first terminal of the capacitor C_2 is as shown in FIG. 2(A).

That is, the voltage abruptly rises with the time constant determined by the values of the capacitors C_1 and C_2 and the resistor R_1 at the instant t_1 at which the key switch K is closed. Soon, the capacitor C_2 is charged up. Thereafter, charging the capacitor C_1 is still continued through a charge resistor R_2 and the ground line, but the current for charging the capacitor C_1 gradually decreases with the time constant mainly determined by the values of the capacitor C_1 and the resistor R_2 after the instant t_1 . Therefore, a voltage at a circuit point X where the capacitor C_1 and the resistor R_2 are connected together decreases toward the ground level, and therefore the capacitor C_2 is discharged through a discharge resistor R_3 .

Thus, the voltage at the output terminal T_1 decreases with the time constant determined mainly by the values of the capacitor C_2 and the resistor R_3 for the period of from the instant t_1 to the instant t_2 and reaches zero volt at the instant t_2 .

After the instant t_2 , the key switch K is opened. As a result, the capacitor C_1 is discharged through the resistors R_1 and R_4 and a diode D_2 , but the voltage at the output terminal T_1 remains unchanged and therefore the waveform of this voltage becomes a straight line as shown in FIG. 2(A) in which the X-axis represents the time while the Y-axis the voltage in dB.

As is shown in FIG. 3, the envelope signal forming circuit 1 having the organization described above is actuated by the key depression in the key board 2 in correspondence to the ON-OFF operation of the key switch provided for each of the keys, and introduces the output voltage of the output terminal T_1 , as an envelope deciding signal EN, to a tone keyer 3, whereby the output signal of a tone generator 4 is fed to a tone coloring circuit 5 through the gating operation of the tone keyer 3. The tone coloring circuit 5 receives the

keyed tone signals having respective envelopes determined by the envelope signal forming circuits which are respectively provided for all the keys, thereby producing a composite signal. This composite signal is applied through an amplifier 6 to a loudspeaker 7.

In this connection, the case where, for instance, two keys are successively depressed at the instants t_1 and t_{1a} whereby two percussive tone signals are produced will be considered. In this case, the waveforms F and F_a of the two percussive tone signals are sometimes overlapped with each other as is shown by a region h hatched with slant lines in FIG. 2(B), thus resulting in the overlapping of two produced tones. Therefore, the composite tone of the two tones thus overlapped is unpleasant and unclear to an auditor and is not crispy.

Furthermore, a conventional tone keying circuit arrangement for producing percussive tones and sustained tones and composite tones of these tones in an electronic musical instrument, as is shown in FIG. 6, comprises a tone keyer 3A for sustained tones (hereinafter referred to as "a sustained tone keyer 3A"), a tone keyer 3B for percussive tones (hereinafter referred to as "a percussive tone keyer 3B"), and an envelope signal forming circuit 1. These tone keyers 3A and 3B and the envelope signal forming circuit 1 are provided for each of the keys in a keyboard 2, and the operation of the percussive tone keyer 3B is controlled by the envelope forming circuit 1.

The conventional tone keying circuit arrangement further comprises a tone generator 4 connected to the inputs of the tone keyers 3A and 3B, and a tone coloring circuit 5 connected to the outputs of the tone keyers 3A and 3B respectively through variable resistors (tone level controls) 8 and 9 which respectively, control the signal levels to be supplied to the tone coloring circuit 5.

In this conventional tone keying circuit arrangement, the sustained tone keyer 3B produces a sustained tone signal S_1 which is sustained for the period of from the instant t_1 at which a key is depressed by a finger or the like to the instant t_2 at which the key thus depressed is released as is shown in FIG. 7(A), while the percussive tone keyer 3B produces a percussive tone signal S_2 which rises first at the instant t_1 and then decays in response to the output of the envelope signal forming circuit 1 as is shown in FIG. 7(B). These outputs S_1 and S_2 are applied, as the output of the tone keying circuit arrangement, through the respective variable resistors 8 and 9 to the tone coloring circuit 5.

In the circuit of FIG. 6, if the variable resistor 9 is set at its maximum attenuation position while the variable resistor 8 is set at its minimum attenuation position, the sustained tone signal S_1 as shown in FIG. 7(A) can be obtained. In contrast, if the variable resistor 9 is set at its minimum attenuation position while the variable resistor 8 is set at its maximum attenuation position, the percussive tone signal S_2 as shown in FIG. 7(B) can be obtained.

In addition, if these variable resistors 8 and 9 are selectively set, different tone signals having different envelopes as shown in FIGS. 7(C) and 7(D) can be obtained.

In this connection, a circuit such as shown in FIG. 8 has been employed as the sustained tone keyer 3A, and a circuit such as shown in FIG. 9 has been employed as the percussive tone keyer 3B together with the envelope signal forming circuit 1.

Thus, it is necessary in the conventional tone keying circuit arrangement to separately provide two tone keyers 3A and 3B for each of the keys. Therefore, the number of circuits and parts in the conventional tone keying circuit arrangement is inevitably great.

SUMMARY OF THE INVENTION

Accordingly, a first object of this invention is to eliminate the above-described difficulties accompanying the conventional envelope signal forming circuit.

A second object of the invention is to provide an envelope signal forming circuit in which a percussive waveform having an abruptly rising portion and a gently decaying portion is obtained, and in the case when the decaying portions of percussive waveforms successively produced are overlapped, the overlapping of the waveforms can be sufficiently reduced.

A third object of the invention is to provide an envelope signal forming circuit which produces an envelope signal output having a controllable waveform such as a percussive waveform, a sustained waveform or a waveform consisting of these waveforms.

A fourth object of the invention is to improve an envelope signal forming circuit to reduce the number of circuits and parts required for a tone keying circuit arrangement.

The foregoing objects and other objects of the present invention will become more apparent from the following detailed description and the appended claims when read in conjunction with the accompanying drawings.

BRIEF DESCRIPTION OF THE DRAWINGS

In the accompanying drawings:

FIG. 1 is a circuit diagram of a conventional envelope signal forming circuit is an electronic musical instrument;

FIGS. 2(A) and 2(B) are graphical representations illustrating envelope signals obtained by the conventional envelope signal forming circuit shown in FIG. 1;

FIG. 3 is a block diagram showing an electronic musical instrument to which the present invention is applied;

FIG. 4 is a circuit diagram illustrating one embodiment of the invention.

FIGS. 5(A) and 5(B) are graphical representations illustrating envelope signals produced from the circuit shown in FIG. 4;

FIG. 6 is a block diagram of a conventional tone keying circuit arrangement in an electronic musical instrument;

FIGS. 7(A), 7(B), 7(C) and 7(D) are graphical representations illustrating keyed tone signal envelopes produced from the conventional tone keying circuit arrangement shown in FIG. 6;

FIG. 8 is a circuit diagram of a tone keyer for sustained tones in the conventional tone keying circuit arrangement shown in FIG. 6;

FIG. 9 is a circuit diagram of a tone keyer for percussive tones together with an envelope signal forming circuit in the conventional tone keying circuit arrangement shown in FIG. 6;

FIG. 10 is a circuit diagram illustrating another embodiment of the invention; and

FIGS. 11(A), 11(B), 11(C) and 11(D) are graphical representations illustrating envelope signals produced by the circuit shown in FIG. 10.

DETAILED DESCRIPTION OF THE INVENTION

With reference to FIG. 4, there is shown a circuit diagram illustrating one embodiment of the envelope signal forming circuit of this invention, which is similar to the circuit diagram of FIG. 1 except that a decay control circuit H is added thereto.

This decay control circuit H comprises a control voltage setting device VR which is, for instance, a variable resistor connected in parallel to the power source E. The sliding piece, or the wiper, of the variable resistor VR is connected to a discharge resistance element which is, for instance, a resistor R₅ connected to a unidirectional element which is, for instance a diode D₃. One terminal (which is an anode in FIG. 4) is connected to the non-ground end of the capacitor C₂. The resistance of the resistor R₅ is selected to be much smaller than that of a resistor R₃ connected in parallel to the capacitor C₂.

The operation of the envelope signal forming circuit shown in FIG. 4 is as follows:

When the key switch K is closed at the instant t₁, the capacitors C₁ and C₂ are charged through the loop which was described with reference to FIG. 1. Soon, the capacitor C₂ is fully charged up. Therefore, the voltage of the output terminal T₁ abruptly rises at the instant t₁ as is shown in FIG. 5(A). Thereafter, the capacitor C₂ is discharged in such a manner that the discharge condition of the capacitor C₂ is determined from the relationship between the voltage at the non-grounded end of the capacitor C₂, that is, the voltage at the anode side of the diode D₃ and the voltage at the cathode side of the diode D₃, that is, the setting voltage of the control voltage setting device VR.

1. In the case where the wiper of the variable resistor VR is positioned at the non-grounded end P₁ thereof or is positioned near the non-grounded end P₁ whereby the setting voltage is higher than the charge voltage of the capacitor C₂, the envelope signal forming circuit will operate as follows:

In this case, the diode D₃ is in OFF state, or is non-conductive. Accordingly the capacitor C₂ is discharged only through the resistor R₃. As a result, the voltage at the output terminal T₁ decreases with the time constant determined mainly from the values of the capacitor C₂ and the resistor R₃, as is shown by a curve I₀ in FIG. 5(A).

2. In the case where the wiper of the variable resistor VR is positioned at the grounded end P₂ thereof whereby the wiper is applied with the ground voltage, the capacitor C₂ which has been charged is now discharged through the diode D₃ and the resistor R₅. Accordingly, the voltage at the output terminal T₁ decreases with the time constant determined mainly from the values of the capacitor C₂ and the resistor R₅ as is shown by a curve b in FIG. 5(A). In this operation, since the resistance of the resistor R₅ is much smaller than that of the resistor R₃ as was described before, the gradient of the curve b is great.

Soon, the charged voltage of the capacitor C₂ decreases, as a result of which the diode D₃ becomes non-conductive. Thereafter, the capacitor is therefore discharged through the resistor R₃. Accordingly, the voltage at the output terminal T₁ decreases at a gradient

which is substantially equal to that of the curve I_0 as is shown by a curve I_1 in FIG. 5(A).

3. In the case where the wiper of the variable resistor VR is positioned at a point between the non-grounded end P_1 and the grounded end P_2 thereof, the envelope signal forming circuit operates in the same manner as in the case of paragraph (2) above except that, when the diode D_3 turns non-conductive, the remaining voltage in the capacitor C_2 is higher than that in the case of paragraph (2) in correspondence to the position of the wiper. Accordingly, the voltage at the output terminal T_1 decreases first along the curve b and then along a curve I_2 or a curve I_3 .

The voltages thus developed at the output terminal T_1 are utilized as the envelope signal EN.

As was described above the capacitor C_2 is discharged through the resistor R_5 of the decay control circuit H, depending on the voltage of the capacitor C_2 . This resistor R_5 is much smaller in resistance than the resistor R_3 of sufficiently high resistance which is connected in parallel to the capacitor C_2 . Therefore, the decaying portion of the waveform of the envelope signal is a controllable waveform consisting of a curve having a sufficiently great gradient and a curve having a relatively small gradient.

The formation of the controllable waveform, as is apparent from FIG. 5(B), contributes to the controlling of the overlapping of, for instance, two keyed tone signal produced at short time intervals. That is, the overlapping of the waveforms can be controlled to be reduced as required, thus remarkably improving unclear and non-crisp tones which may be created by the overlapping of the tones.

Thus, merely by the provision of the decay control circuit H simple in composition, the decaying waveform which is substantially the same, in the rising portion of the waveform, its peak value and the decaying portion having a relatively gentle gradient, as the decaying waveform obtained by the conventional envelope signal forming circuit and which accordingly has a percussive tone characteristic substantially equal to that of the decaying waveform obtained by the conventional keying arrangement can be obtained.

The decay control circuit H shown in FIG. 4 is not limitative. That is, all that is necessary for the composition of this circuit H is that when the charged voltage in the capacitor C_2 becomes lower than the setting voltage, the discharge paths of the capacitor C_2 are interchanged.

Hereinafter, another example of the envelope forming circuit provided according to another aspect of the invention will be described, being embodied in the tone keying circuit arrangement shown in FIG. 6.

This example, or the envelope forming circuit 1, as is shown in FIG. 10, comprises two charge-discharge capacitors C_1 and C_2 . One terminal of the capacitor C_1 is connected to one terminal of the capacitor C_2 through a reverse-current blocking element D_1 such as a diode. The other terminal of the capacitor C_1 is connected to the positive terminal of the power source E through a charge resistor R_1 and the key switch K, while the other terminal of the capacitor C_2 is grounded. A charge resistor R_2 for charging the capacitor C_1 is connected in parallel to a series circuit of the diode D_1 and the capacitor C_2 . A series circuit of a discharge resistor R_4 having a relatively high resistance and a diode D_2 is connected in parallel to a series circuit

circuit of the capacitor C_1 and the resistor R_1 . Furthermore, a discharge resistor R_3 which is much higher in resistance than the resistor R_2 is connected in parallel to the capacitor C_2 to which an output terminal T_1 is connected.

It can be readily understand that a circuit composed of the circuit elements described above is known in the art, when compared with that of FIG. 1. To the circuit thus composed a resistance varying circuit RU comprising, for instance, a field-effect transistor FET is added, according to the invention, as is shown in FIG. 10.

The gate of the transistor FET is connected to the control voltage terminal of a control voltage setting device VR such as a variable resistor connected across the power source E. If necessary, the gate of the transistor FET may be connected through a resistor R_5 to the control voltage terminal, or the wiper of the variable resistor VR.

When the wiper of the variable resistor VR is positioned at the grounded end P_2 of the variable resistor, the ground voltage is applied to the gate of the transistor FET, and accordingly the transistor FET becomes non-conductive, that is, the transistor FET shows its maximum resistance.

On the other hand, when the wiper is positioned at the other end P_1 of the variable resistor VR, the maximum voltage of the power source is applied to the gate of the transistor FET, and accordingly the transistor FET becomes conductive, that is, the transistor FET shows its minimum resistance.

Thus, if the wiper is moved to position at a point between the grounded end P_2 of the variable resistor VR and the other end P_1 , the transistor FET will show a resistance between its maximum and minimum resistances in correspondence to the moving quantity of the wiper.

In FIG. 10, reference characters Ga and Gb designate terminals to which the corresponding portions of the other envelope signal forming circuit respectively provided for the other keys in the keyboard are connected.

1. In the case where the wiper of the variable resistor VR is positioned at the grounded end P_2 thereof, the operation of the envelope signal forming circuit shown in FIG. 10 is as follows:

In this case, the transistor FET is non-conductive as was described above. Therefore, the capacitors C_1 and C_2 are charged through a loop consisting of the power source E, the key switch K, the resistor R_1 , the capacitor C_1 , the diode D_1 , the capacitor C_2 , and the ground line.

In this charge operation, a time constant is sufficiently small, being determined by the values of the capacitors C_1 and C_2 and the resistor R_1 . Accordingly, a voltage at the output terminal T_1 abruptly rises at the instant t_1 at which the key switch K is closed, as shown in FIG. 11(A). Soon, the capacitor C_2 is fully charged up, but charging the capacitor C_1 is continued through the resistor R_1 . Therefore, a voltage at the connecting point X of the capacitor C_1 and the resistor R_2 decreases to the ground potential according to the decrease of the charge in the capacitor C_1 , and whereupon the capacitor C_2 is discharged through the resistor R_3 . Accordingly, the waveform of a voltage at the output terminal T_1 becomes a decaying waveform V_1 which decays at a gradient determined mainly by the

values of the capacitor C_2 and the resistor R_3 as is shown in FIG. 11(A).

Thereafter, the key switch K is opened at the instant t_2 and simultaneously the capacitor C_1 starts to discharge through the resistors R_1 and R_4 and the diode D_2 . However, at the instant t_2 the voltage at the output terminal T_1 remains unchanged because the capacitor C_2 has already been discharged and the diode D_1 blocks a negative going change.

2. In the case where the wiper of the variable resistor VR is positioned at the non-grounded end P_1 , the envelope signal forming circuit operates as follows:

In this case, the transistor FET is conductive. When the key switch K is closed at the instant t_1 , the capacitors C_1 and C_2 are charged through the loop in the same manner as in the case described above, and soon the capacitor C_2 is fully charged up. Then, a potential at the connecting point X is maintained at a voltage determined by the voltage dividing ratio of the resistor R_1 to the resistor R_2 , that is, a voltage approximately equal to the voltage of the power source in this case, since the capacitor C_1 is shunted by the conductive transistor FET. Accordingly, the potential at the output terminal T_1 is maintained unchanged until the time instant t_2 at which the key switch K is opened.

Upon opening of the key switch K, the capacitor C_2 starts to discharge with a time constant determined mainly by the values of the capacitor C_2 and the resistor R_3 .

Thus, the voltage at the output terminal T_1 has a sustained waveform V_2 which is similar to a keying waveform as is shown in FIG. 11(D).

3. In the case where the wiper of the variable resistor VR is positioned at a point between the both ends P_1 and P_2 of the variable resistor VR, the envelope signal forming circuit operates as follows:

In this case, the capacitor C_1 is bypassed by the resistance of the transistor FET. Therefore, after the capacitor C_2 has been fully charged up through the loop by closing the key switch K, a potential at the connecting point X is maintained at a voltage determined by the voltage dividing ratio of the sum of the resistances of the resistor R_1 and the transistor FET to the resistance of the resistor R_3 . Accordingly, the capacitor C_2 is discharged by as much as the difference voltage between the voltage at the connecting point X and the voltage of the capacitor C_2 .

Thus, the voltage at the output terminal T_1 has a waveform V_3 consisting of a decaying waveform portion v_1 which abruptly rises at the instant t_1 and then decays and a sustained waveform portion v_2 which succeeds to the decaying portion v_1 , as is shown in FIGS. 11(B) and 11(C).

The level of the sustained waveform v_2 is determined by the resistance of the transistor FET, or by the posi-

tion of the wiper of the variable resistor VR. Accordingly, when the wiper is positioned near the grounded-end P_2 of the variable resistor VR, the level of the sustained waveform v_2 is relatively low as is shown in FIG. 11(B), while when the wiper is positioned near the non-grounded end P_1 of the variable resistor VR, the sustaining level is relatively high as is shown in FIG. 11(C). In this way, the level of the sustained waveform portion v_2 can be controlled by means of the control voltage setting device, that is, the variable resistor VR.

Thus, according to the invention, an envelope signal having a controllable waveform such as a decaying waveform, a sustained waveform or a waveform consisting of these waveforms can be obtained, and the control of the waveforms can be continuously carried out through a simple circuit, that is, the resistance varying circuit RU connected in parallel to the capacitor C_1 of the envelope signal forming circuit 1.

Accordingly, when the present invention is applied to a tone keying circuit arrangement in an electronic musical instrument, only one switching circuit can control all of the keys of one keyboards. Therefore, the number of circuits and parts in the tone keying circuit arrangement can be reduced to be much smaller than that of the conventional tone keying circuit arrangement. For instance, a conventional tone keying circuit arrangement having 61 keyboards has 122 tone keyers, but this number of tone keyers can be reduced to 61 according to the invention.

I claim:

1. In an improved envelope signal forming circuit having a first charge-discharge capacitor, a diode, a second charge-discharge capacitor connected through said diode to said first charge-discharge capacitor, a first charge resistor connected in parallel to a series circuit consisting of said diode and said second charge-discharge capacitor, and a second discharge resistor connected in parallel to said second charge-discharge capacitor for producing as an envelope signal the voltage of said second charge-discharge capacitor, the improvement which comprises:

a field-effect transistor to control the envelope signal having a decaying waveform, said field-effect transistor having its drain and source electrodes directly connected across said first charge-discharge capacitor; and

a control voltage setting device comprising a variable resistor and a power source connected in parallel thereto, the wiper arm of said variable resistor being connected to the gate electrode of said field-effect transistor, the resistance of said field-effect transistor being controlled by the voltage set by said variable resistor to control the envelope signal.
